UNITED STATES PATENT OFFICE

144,815

DESIGN FOR A HOUSING FOR DISPENSING APPARATUS

Carl W. Sundberg, Birmingham, Mich., assignor to Bowser, Inc., Fort Wayne, Ind., a corporation of Indiana

Application July 30, 1945, Serial No. 121,074

Term of patent 14 years

(Cl. D52—2)

To all whom it may concern:

Be it known that I, Carl W. Sundberg, a citizen of the United States, residing in the city of Birmingham, county of Oakland, State of Michigan, have invented a new, original, and ornamental Design for Housing for Dispensing Apparatus, of which the following is a specification, reference being had to the accompanying drawing, forming a part thereof.

The single figure is a perspective view of a housing for dispensing apparatus embodying my new design. The opposite side of the housing is of substantially the same appearance as the side shown.

I claim:

The ornamental design for a housing for dispensing apparatus, as shown and described.

CARL W. SUNDBERG.
